UNITED STATES PATENT OFFICE.

McCLINTOCK YOUNG, OF FREDERICK, MARYLAND, ASSIGNOR TO THE
PALMETTO FIBER COMPANY, OF ILLINOIS.

DESIGN FOR A BRUSH.

SPECIFICATION forming part of Design No. 25,518, dated May 19, 1896.

Application filed April 18, 1896. Serial No. 588,192. Term of patent 14 years.

To all whom it may concern:

Be it known that I, MCCLINTOCK YOUNG, a citizen of the United States, residing at Frederick, in the county of Frederick and State of Maryland, have invented and produced a new and original Design for Brushes, of which the following is a specification, reference being had to the accompanying drawings, in which—

Figure 1 is a side elevation of a brush embodying my improved design. Fig. 2 is an elevation of the rear side of the same. Fig. 3 is an elevation of the opposite side of the brush.

The leading features of my design consist of the brush-block, presenting in outline a rear flat face, a handle curved outward and rearward therefrom, a front face joining the rear face by curves at its ends, and bristles radiating from the front face of the block and terminating in a line parallel therewith.

A represents the brush block or body, presenting in outline, as viewed from the side, as in Fig. 1, a flat rear face *a*, from which rises an outwardly and rearwardly curved handle *b*. The rear edge *c* of the handle consists of a uniform outward curve joining the ends of the brush-block, while the inner edge *c'* of the handle presents two curves, each starting from the face of the block, as at *c*², at points inward of the ends and extending thence upward parallel with the outer edge of the han-

dle to its center, whence the curves drop and join in a point, as at *d*. The front face of the block extends for a portion of its length parallel with the rear face and joins the same at its ends in curves *e*. The bristles radiate 35 from the front face of the block and terminate in a line, as at *f*, curved at its ends and extending parallel to the block.

As viewed from the rear, the brush-block is rectangular in form, the handle being also rectangular and extending parallel with the sides of the block, while the bristles terminate at their ends in straight lines *g*, parallel with the ends of the block.

As viewed from the front, the brush-block 45 is rectangular in form, with the bristles presenting an outline *h*, also rectangular in form, and extending at its ends beyond the ends of the block.

Having thus described my invention, what 50 I claim is—

The design for a brush substantially as herein shown and described.

In testimony whereof I have hereunto set my hand in the presence of two attesting witnesses.

MCCLINTOCK YOUNG.
